(57) **CLAIM**

The ornamental design for a sofa cover, as shown and described.

DESCRIPTION

FIG. 1 is a front perspective view of a sofa cover, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a partial enlargement of FIG. 4; and,

FIG. 9 is a partial enlargement of FIG. 6.

The dash-dot broken lines in the figures are demarcating enlarged areas and form no part of the claimed design.
